(57) **CLAIM**

We claim the ornamental design for portions of post mountable mail boxes, as shown and described.

DESCRIPTION

FIG. 1 is a perspective view showing front, top, and right side for portions of post mountable mail boxes of our new design;

FIG. 2 is a front elevational view thereof;

FIG. 3 is a right side view thereof;

FIG. 4 is a rear elevational view thereof;

FIG. 5 is a left side view thereof;

FIG. 6 is a top plan view thereof; and,

FIG. 7 is a bottom plan view thereof.

The broken-line disclosure found in several of the drawing views is provided for illustrative purposes only and forms no part of the claimed design.
